UNITED STATES PATENT OFFICE.

FREDERIC WILLIAM CUNARD, OF LIVERPOOL, ENGLAND.

PORTABLE REDOUBT FOR MILITARY USE.

1,262,926.

Specification of Letters Patent. Patented Apr. 16, 1918.

Application filed October 30, 1916. Serial No. 128,452.

To all whom it may concern:

Be it known that I, FREDERIC WILLIAM CUNARD, a subject of the King of England, residing at 98 Upper Canning street, Liverpool, in the county of Lancaster, England, engineer, have invented certain new and useful Improvements in or Relating to Portable Redoubts for Military Use, of which the following is a specification.

- 10 This invention relates to a movable bullet-proof shield or redoubt for military use in the field, and has for its object to provide a structure which may be propelled with comparative ease over broken or soft ground.
- 15 A shield or redoubt, according to my invention, comprises a front shield portion proper which is preferably of curved or undulating shape or configuration in order to deflect bullets which may strike same and 20 is provided with side extensions and a top or roof, if desired. Said shield may be painted with spiral markings of color similar to that of the ground in order to lessen its visibility to the enemy's artillery.
- 25 Said shield is mounted on side frame members which are supported on two pairs of wheels and extend rearwardly, so that by reason of the balancing of the structure, or 30 through downward pressure exercised on the rear portion of the frame, the front wheels may rise in see-saw fashion to facilitate the movement of the structure over broken ground and prevent it from capsizing front or rearwardly. At each side I 35 employ a side balancing rod or lever as a preventive against capsizing sidewise.

As means for driving the structure, I prefer to employ the propelling mechanism as hereinafter described.

40 I will further describe my invention with the aid of the accompanying sheet of explanatory drawings, in which:—

Figure 1 is a side elevation, and

Fig. 2 is a plan of a movable shield or 45 redoubt.

Figs. 3 to 5, inclusive, illustrate means or mechanism whereby the structure may be propelled, and

50 Figs. 6 to 11, inclusive, illustrate a modified construction and arrangement of propelling mechanism.

In the several views of the drawings like characters of reference denote like or equivalent parts wherever they occur.

55 Referring first to Figs. 1 and 2,

1 denotes a steel shield which is constructed of curved shape or configuration with the object of causing impinging bullets to be deflected without piercing same; if desired, for the purpose of affording additional protection, said shield may be formed with rearwardly extending side members 2—as indicated by the dotted lines Fig. 1—and also a roof or top.

The lower end of said shield 1 is secured 65 in a slotted or channeled piece 3 supported on the side frame members 4, and said shield is stayed from the frame by means of the rods 5, 6, 7, 8.

Each of the side frame members 4 is 70 suitably supported at the front on the transverse piece 8^a and at the rear on the square block 8^b mounted on the tubular shaft 25, hereinafter referred to, and on each side is disposed a balance lever 10, 10^a, which lever 75 is movable about a pivot 11 supported on the shield 1; arm 10 of each of said levers 10, 10^a is provided with a wheel or roller 12 and arm 10^a constitutes or is formed into or provided with a handle. 80

Should the ground over which the structure is to be moved be uneven or rough, one or other of said levers 10, 10^a is moved through an angle of 45° so that arm 10 turns outwardly and a wheel or roller 12—by 85 contact with the ground—prevents the capsizing of the structure. The rear extensions of said side frame members 4 are provided with wheels or rollers 13 which come into contact with the ground if the structure is 90 being moved up an incline or over broken ground, thus preventing it from capsizing rearwardly, and through the balance, or by downward pressure of said rear frame extensions the front wheels (5) are raised to 95 enable the structure to be moved forwardly in see-saw fashion.

The front axle is designated 14 and the field wheels mounted thereon 15 (ball bearings being preferably employed in said 100 wheels) and when said axle is turned about its pivotal center 16, in which there are also preferably ball bearings, said wheels 15 merely move said arms 10 out of their paths, said lever arms being of course free to be 105 displaced about their pivots or hinges; or, alternatively they may be moved by an operator of the structure.

110 Preferably said front axle 14 is provided with strengthening frames 17, 17^a, the quad-

rants 17^a whereof are adapted to move in contact with ball bearings disposed on the undersides of the front ends of the frame members 4 to facilitate the steering of the structure 5 over rough or holding ground.

18 in Fig. 2 indicates curved plates secured to a lower transverse piece with the object of protecting the frail portion of the springs—not shown.

10 Said front wheels 15 are steered by the actuation of axle 14 by any suitable mechanism operated through the movement of steering wheel 19—Fig. 2.

15 At the bottom of the structure—Fig. 1—there is hinged or pivoted at 20 a steel trailer 21 designed to protect the legs of the men behind the structure.

20 The propelling wheels designated 22 may if required be provided with disks or plates 23 for the purpose of affording protection from enfilading fire.

25 24 indicates a machine gun mounted on the structure which may be provided with loopholes for rifles and apertures for barbed wire cutting implements.

30 Reference is now made to the motion transmission gearing illustrated in Figs. 3 to 5, in which Figs. 3 and 4 are elevations viewed at right angles to each other, and Fig. 35 5 is an inverted plan of the upper "dome" gear wheel hereinafter described. Disposed around said rear axle 9 is a tubular shaft or sleeve 25, 25^a, mounted on ball bearings 26—Fig. 4—on the portion 25^a of which sleeve are formed flats whereon is mounted a rectangular block 27 to which are secured, by means of the bolts 28, the lower side limbs or members 29 of a frame 29—30.

35 On the lower horizontal member of said frame portion 30 there is provided a ball bearing 31 above which is arranged a dome gear wheel 32 provided on its upper face with rectangular lugs or projections 33, adapted to take into corresponding socket 40 passages formed in a base block 34 which is integral with a rod or spindle 35 extending upwardly, and being maintained in position when passing through a recess in the upper horizontal member of said frame 30, by 45 means of a clamping plate 36; said rod 35 is prevented from upward displacement by means of a collar 37 pinned thereon.

50 An actuating wheel 38 is secured to the upper end of said rod or spindle 35.

55 Said dome gear wheel 32 revolves about a vertical rod or shaft 39 which, extending upwardly from said block 27, passes through a bearing boss 40 formed on the lower horizontal member of said frame portion 30 and 60 terminates in a socket 41 provided in the enlarged end 35^a of said vertical rod or shaft 35.

Secured to or forming part of the lower end of said block 27 is a second or tail rod 65 or spindle 42 on which is revolvably mounted

a dome gear wheel 43 supported on said rod by means of a collar 44.

Said block 27 is maintained in the desired position on said sleeve 25, 25^a on the one side by the shoulder 45 formed by reducing the 70 sleeve at this part, and on the other side by the collar 46.

75 Revolvably mounted on said sleeve 25—being maintained in position by means of a collar 47—is a wheel 48 provided with two sets of ball teeth 49, 50, of which set 49 is engaged by the dome gear wheel 32, and set 50 engages the dome wheel 43, which wheel 43, in turn, also engages with the ball teeth 51 of a wheel 52 firmly keyed on to the axle 9. 8

Thus, when said hand wheel 38 is rotated motion is transmitted to a wheel 52 through the engagement of dome wheel 32 with the teeth 49 of wheel 48 mounted on the tubular fulcrum shaft 25, the engagement of teeth 50 8 of wheel 48 with dome wheel 43, and the engagement of said wheel 43 with the teeth 51 of wheel 52 keyed to axle 9.

Said wheel 52 is prevented from lateral displacement by means of a removable collar 53, and a collar 54 permanently secured to axle 9. If, however, it be desired at any time to render said gearing temporarily inoperative, said collar 53 is removed and said wheel 52 is slid out of gear with dome wheel 43; then by replacing the collar 53 on the axle at the other side of said wheel 52, said latter wheel is maintained out of engagement with wheel 43.

As shown in Fig. 2, two sets of said transmission gearing are employed.

Referring now to the modifications illustrated in Figs. 6 to 11, there is mounted on said tubular shaft or sleeve 25, 25^a, disposed on axle 9, a rectangular block or collar 27 which carries a tail spindle 42 whereon is revolvably disposed a wheel 53 on which are ball teeth 54.

On said tubular shaft is mounted a block piece or collar provided with a socket 55 adapted to receive a rod or pole of wood or metal; and on one side of said block is formed a portion of a dome wheel 56; on the other side of said block are formed teeth 57. Keyed on to said shaft are a toothed wheel 58 and a domed wheel 59.

As illustrated in Fig. 6, gear wheel 53 is in engagement with the part-dome wheel 56 and with dome wheel 59. When the pole or rod in said socket is pulled down said block piece is moved through one quarter of a revolution; then said block is moved laterally, and as same is connected with same collar by means of the rods 60 said wheel 57 will move into engagement with wheel 58; then on the reverse stroke of the rod said axle is carried forward a further quarter of a revolution.

Said gearing being noiseless is adapted for night attacks where silence is essential.

In some cases said structure may be pro-

pelled by means of a petrol or electric motor, and wheels of the caterpillar type may be employed.

Having now described my invention what 5 I claim as new and desire to secure by Letters Patent is:—

1. A movable bullet proof shield or redoubt for military use in the field comprising a shield portion which is preferably of 10 curved shape or configuration mounted on frame members which are supported on two pairs of wheels and extend rearwardly so that either through the balance or by downward pressure the front wheels may rise in 15 see-saw fashion to facilitate the movement of the structure over broken ground and prevent the shield from capsizing front or rearwardly; and hinged or pivoted side balancing rods or levers for the purpose of preventing the capsizing sidewise of the structure; substantially as described. 20

2. A movable bullet proof shield or redoubt for military use in the field comprising—

ing a shield portion which is preferably of curved shape or configuration mounted on 25 frame members which are supported on two pairs of wheels and extend rearwardly so that either through the balance or by downward pressure the front wheels may rise in 30 see-saw fashion to facilitate the movement of the structure over broken ground and prevent the shield from capsizing front or rearwardly; and hinged or pivoted side balancing rods or levers for the purpose of preventing the capsizing sidewise of the structure; and gearing for propelling said structure which essentially embody a gear wheel or wheels provided with ball teeth and a gear wheel or wheels having domed recesses; 35 substantially as described. 40

In witness whereof I have hereunto set my hand this 13th day of October, 1916.

FREDERIC WILLIAM CUNARD.
